UNITED STATES PATENT OFFICE.

SALOMON DAVIDSON, OF NEW YORK, N. Y.

DESIGN FOR A CHAIN-LINK.

SPECIFICATION forming part of Design No. 13,047, dated July 18, 1882.

Application filed May 31, 1882. Term of patent 7 years.

To all whom it may concern:

Be it known that I, SALOMON DAVIDSON, a citizen of the United States, residing at New York, in the county and State of New York, have invented and produced a new and original Design for Chain-Links, of which the following is a specification, reference being had to the accompanying drawings, forming part thereof.

10 This design consists of a "box," so called, having notches in its edges, longitudinal slots in its sides, and holes adjacent to the opposite ends of the slots, and a filling-piece which is visible through said notches, holes, and slots.

15 In the accompanying drawings, Figure 1 shows the design applied to a long link. Fig. 2 shows it applied to a short link. Fig. 3 is a sectional view of one of the links.

Similar letters indicate corresponding parts.

20 The letter A designates the box; B, the notches; C, the slots; D, the holes, and E the filling-piece. The box is square or polygonal, and the notches B are formed in each of its edges, they being angular in shape. The slots C are rectilinear, and extend longitudinally of the box, one in each side, while the holes D are adjacent to the opposite ends of the slots respectively in the sides of the box. The filling-piece E is within the box, and extends approximately the entire length thereof, thus being visible through said notches, slots, and holes.

By these characteristic features a novel and distinguishing appearance is imparted to the link.

What I claim as new, and desire to secure 35 by Letters Patent, is—

1. The design for a chain-link, consisting of a box having notches in its edges and longitudinal slots in its sides, as shown and described.

2. The design for a chain-link, consisting of a box having longitudinal slots in its sides and holes adjacent to the opposite ends of the slots, as shown and described.

3. The design for a chain-link, consisting of 45 a box having notches in its edges, longitudinal slots in its sides, and holes adjacent to the opposite ends of the slots, as shown and described.

4. The design for a chain-link, consisting of 50 a box having notches in its edges, longitudinal slots in its sides, and holes adjacent to the opposite ends of the slots, and of a filling-piece within the box, as shown and described.

In testimony whereof I have hereunto set my 55 hand and seal in the presence of two subscribing witnesses.

SALOMON DAVIDSON. [L. S.]
